US00D755010S

(12) **United States Design Patent**
Wu

(10) **Patent No.:** **US D755,010 S**
(45) **Date of Patent:** **** May 3, 2016**

(54) **GRILL SURFACE**

(71) Applicant: **Tsann Kuen (Zhangzhou) Enterprise Co., Ltd., Zhangzhou (CN)**

(72) Inventor: **Han-Ming Wu, New Taipei (TW)**

(73) Assignee: **Tsann Kuen (Zhangzhou) Enterprise Co., Ltd., Zhangzhou (CN)**

(**) Term: **14 Years**

(21) Appl. No.: **29/506,682**

(22) Filed: **Oct. 17, 2014**

(30) **Foreign Application Priority Data**

Apr. 16, 2014 (CN) 2014 3 0091683

(57) **CLAIM**

The ornamental design for a grill surface, as shown and described.

DESCRIPTION

FIG. 1 is a front view of a grill surface showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken line showing in Figures is for illustrative purposes only and forms no part of the claimed design.
